UNITED STATES PATENT OFFICE.

JOHN JAMES, OF NEW YORK, N. Y.

CUT-OFF-VALVE GEAR FOR STEAM-ENGINES.

SPECIFICATION forming part of Letters Patent No. 254,483, dated March 7, 1882.

Application filed April 9, 1881. (No model.)

To all whom it may concern:

Be it known that I, JOHN JAMES, of the city and county of New York, in the State of New York, have invented a certain new and useful

5 Improvement in Cut-Off-Valve Gear for Engines, of which the following is a specification.

When a locomotive-engine is fitted with any of the ordinary forms of link-motion operating a main or distribution slide-valve the variation 10 of the cut-off of the said main or distribution valve is effected by varying the relative positions of the link and link-block. This variation is limited, however, on account of the ensuing prejudicial distribution inherent to the 15 link-motion operating a single valve when much linking-up is attempted. Notwithstanding this the link-motion, in conjunction with a single valve, is still almost universally applied to locomotives, and mainly on account of the 20 simplicity of such arrangement. If, however, a separate cut-off slide-valve could be applied to a locomotive-engine which did not entail the usual amount and complexity of mechanism for varying the point of cut-off, the advantages 25 would be evident. This is the object of my invention. I apply a separate cut-off slide-valve, consisting of a single plate driven by a lever from some of the reciprocating parts—such as the piston-rod or cross-head—of the engine, and having an invariable movement or 30 travel relatively to the engine-piston. Such cut-off valve has a fixed (instead of a variable) travel, and a fixed (instead of a variable) length. Ordinarily the cut-off of a cut-off valve is varied 35 by varying the travel of the cut-off valve, or by varying the length or lap of the cut-off valve, or by varying the angle between the special cut-off eccentric and the crank. My method of varying the cutting-off action of 40 the cut-off valve is to vary the travel of the main valve by altering the relative positions of the link and link-block in the ordinary link-motion. This arrangement is advantageous, because of its simplicity and paucity of parts, 45 and because by it can be secured both an earlier and a greater variation of cut-off with better distribution than is possible when the link-motion operating a single slide-valve alone is used.

50 In the accompanying drawings, Figure 1 represents a longitudinal vertical section through

a portion of an engine embodying my invention, and Figs. 2 and 3 represent two diagrams for illustrating the working advantages of my invention.

55

Referring first to Fig. 1, A designates an engine-cylinder, and B the piston thereof.

C designates the crank-shaft, and motion is transmitted from the piston to said crank-shaft through the piston-rod B', cross-head D, and 60 connecting-rod D' in the ordinary way.

Upon the cylinder is the valve-chest A', in which is the usual main or distribution slide-valve, E, which is secured to the valve-rod E', connected with an arm of the rock-shaft F. 65 The other arm of the rock-shaft carries a block, a, which fits in a link, G, operated by the eccentrics G' G².

H designates the reversing or link-adjusting lever, which is connected with the link G by 70 the rod I, the bell-crank J, and the suspension-link J'.

So far as described the engine is like engines in common use, and as the operation of the link-motion is well understood, further description thereof is unnecessary.

75

Upon the back of the main or distribution slide-valve E is mounted a cut-off slide-valve, K, consisting of a single plate, which is of fixed length, and controls the passage of steam 80 or other motive agent through the ports b of the main valve.

L designates a rock-shaft supported in suitable bearings, and having arms projecting in opposite directions from it. To one of said arms is connected the valve-rod K' of the cut-off slide-valve K, and to the other arm is connected a rod, L', which is connected with the cross-head D, and imparts an oscillating motion to the rock-shaft L, and effects the operation 85 of the cut-off valve.

It will be clearly seen that the cut-off valve is not adjustable in its travel, and that therefore its movement or travel is always the same 90 relatively to the piston.

95

The principles on which my invention is based may be illustrated by the aid of diagrams Figs. 2 and 3, and in such diagrams I will suppose my invention applied to an ordinary double-cylinder steam or compressed-air locomotive with its cranks at right angles and fitted with the ordinary link-motion. I take 100

the following dimensions respectively, first, for the case where the cut-off valve cuts off with its inner edges and its motion is coincident with the piston, (diagram I;) and, second, where the cut-off valve cuts off with its outer edges and its motion is reverse to the piston. These dimensions are chosen simply for illustration, and of course may be varied.

Fig. 2, maximum main-valve travel, two inches; cut-off-valve travel, one inch; main-valve lap, five-sixteenths inch; cut-off-valve lap, thirteen-sixteenths inch; angular advance of eccentrics, twenty degrees; length of eccentric-rods, six times lift of link; open eccentric-rods, (suppose.) Fig. 3, maximum main-valve travel, two inches; cut-off valve travel, one and one-fourth inch; main-valve lap, one-fourth inch; cut-off-valve clearance, three-eighths inch; angular advance of eccentrics, twenty degrees; length of eccentric-rods, six times lift of link; crossed eccentric-rods, (suppose.)

Let $b a l e' l$ be travel-circle of eccentrics. Draw two diameters, $c a, c b$, at right angles. Make $a e e'$ equal to the angular advance, with the center on the diameter $c b$ produced, and radius equal to three times the rectilineal distance between e' and e . Describe the arc $e' e^2 e^3 e$, a line drawn from any point in which arc to the center is approximately the virtual eccentric radius for the relative position of the link and link-block corresponding to that point. With the same radius ($3 e' e$) and center on the same diameter, but one-half the cut-off-valve travel to the left in diagram Fig 2, or to the right in Fig. 3, describe the arc $e^4 e^5 e^6$. Divide the arc $e' e^2 e^3 e$ into a number of parts—say the upper half into three equal parts—and draw $e' e^4 e^2 e^5 e^3 e^6$ parallel to $c b$. Draw $l l$ and $l' l'$ parallel to and at distances from $a c$ equal respectively to the lap of the main valve, and to the lap of the cut-off valve in Fig. 2, or the clearance thereof in Fig. 3. Join $e^4 c e^5 c e^6 c$ with the center c and radii $e^4 c e^5 c e^6 c$. Describe arcs intersecting the line $l' l' l' l$ in $l' l' l' c$, respectively, and join $l' c l' l' c l' c$. Then the angles $e^4 c l' e^5 c l' e^6 c l' c l'$ are the angles of the crank at which cut-off takes place corresponding respectively to the positions of the link relative to the link-block which correspond with $e' e^2 e^3$.

Referring to Fig. 2, it will be noticed that as the link moves from full to mid gear the cut-off takes place earlier, and that with the dimensions chosen the latest cut-off is about three-fifths, and when the link is in the position corresponding to e^3 that the cut-off takes place about one-sixth of the piston-stroke. Now when the link-motion alone is applied and the dimensions (lap lead eccentric throw) usual to locomotives taken, the cut-off takes place, when the link is in a position corresponding to e^3 at approximately half-stroke. Hence when my invention is applied I have both earlier and greater variation of cut-off with better distribution.

It ought to be remarked here that even al-

though the locomotive-cylinders are made sufficiently large so that the latest admissions required are much less than half-stroke, yet it will be generally advisable, in order that the engine may be able to start at any point of the revolution, that the full-gear admissions be made somewhat later than half-stroke. To insure starting, therefore, the dimensions must be so taken that the angle $e^4 c l'$ is at least greater than a right angle.

Referring to Fig. 3, it will be seen that as the link moves from full-gear toward but to a position somewhat short of mid-gear, the cut-off takes place later in the piston-stroke. With the dimensions chosen the earliest cut-off takes place about one-tenth, and when the link is in the position corresponding to about e^3 the cut-off of both main and cut-off valves is simultaneous and takes place about three-fifths of the stroke. Hence with my invention we have earlier and greater variation of cut-off with better distribution than with the link-motion alone.

It is evident, with the dimensions chosen, a cut-off at approximately three-fifths is the latest possible, as, if the link moves from the position where that cut-off is effected, either toward full or mid gear, the cut-off takes place earlier, being effected in the latter instance by the main valve. In order that the engine may start at all points of the revolution, the latest cut-off must be at least later than half-stroke, and this is insured when the cut-off-valve clearance is taken greater than the main-valve lap. In both cases the range of cut-off depends on the dimensions chosen, and when, as will be usually desired, an early cut-off is in conjunction with a cut-off as late as or somewhat later than half-stroke, it will usually tend to a better distribution to give some over-travel to the main-valve when in full-gear, to have crossed eccentric-rods and to take the angular advance small. Where my invention is applied there is not the same necessity for a considerable angular advance—at least so far as pre-release is concerned—because usually the working-fluid will be expanded to a greater degree than when the link-motion only is applied, and consequently will exhaust at less pressure.

It will be evident that if the cut-off valve were constructed to cut-off upon its inner edges it should travel with the piston instead of reversely thereto, and hence the valve-rod K' should be connected below the rock-shaft L instead of above, as here shown.

I am aware that it is old to employ, in connection with a main valve and link-motion for operating the same, a cut-off valve composed of two plates or parts adapted to be adjusted nearer to or farther from each other for varying the point of cut-off by means of a valve-stem having right and left hand threads which engage with corresponding nuts in the two plates or parts of the valve. Such cut-off valve is not off fixed length, like mine, but of variable length, and its length is varied for the purpose of varying the point of cut-off.

I do not claim the above as of my invention.

By driving the cut-off valve in this combination by a connection with the piston-rod or cross head of the engine the movements of the said valve correspond exactly with the movements of the piston in both directions, whereas when the cut-off valve is driven by an eccentric the movements of the said valve, owing to the changing angles of the connecting-rod of the eccentric, do not exactly correspond with the movements of the piston in both directions.

What I claim as my invention, and desire to secure by Letters Patent, is—

In an engine, the combination, with a main

or distribution slide-valve, and an ordinary link-motion for varying the motion thereof, of a cut-off slide-valve consisting of a single plate driven by a connection with the piston-rod or cross-head of the engine, so that it has an invariable travel and an invariable motion relatively to the piston, substantially as and for the purpose specified.

JOHN JAMES.
